DESIGN FOR A COMBINED WATER CLOSET TANK AND BOWL

Bernard B. Pieslak, Abingdon, Ill., assignor to Abingdon Sanitary Manufacturing Company,
Abingdon, Ill., a corporation of Illinois

Application July 12, 1940, Serial No. 93,589

Term of patent 7 years

To all whom it may concern:

Be it known that I, Bernard B. Pieslak, a citizen of the United States, residing at Abingdon, in the county of Knox and State of Illinois, have invented a new, original, and ornamental Design for a Combined Water Closet Tank and Bowl, of which the following is a specification, reference being made to the accompanying drawing, forming a part thereof.

In the drawing,

Fig. 1 is a perspective view of a combined water closet tank and bowl embodying my new design; and

Fig. 2 is a side view thereof.

I claim:

The ornamental design for a combined water closet tank and bowl, substantially as shown.

BERNARD B. PIESLAK.
